BIN CONVEYER

Haskell C. Carter, Portland, Oreg., assignor to
Iron Fireman Manufacturing Company, Port-
land, Oreg.

Application September 18, 1934, Serial No. 744,549

4 Claims. (Cl. 198—64)

This invention relates generally to underfeed stokers, and particularly to bin conveyors to be used in connection therewith.

The main object of this invention is the provision of an exceedingly simple and efficient form of conveyor which is so constructed as to make it extremely flexible as far as adapting itself to installation requirements is concerned.

The second object is the provision of a bin conveyor whereby coal may be conveniently transported from a storage bin to the fuel feeding mechanism of an underfeed stoker.

I accomplish these objects in the manner set forth in the following specification as illustrated in the accompanying drawings, in which:

Fig. 1 is a plan of the device showing the bin walls broken away in a horizontal section.

Fig. 2 is a vertical section taken along the line 2—2 in Fig. 1.

Fig. 3 is a vertical section taken along the line 3—3 in Fig. 1.

Fig. 4 is a vertical section taken along the line 4—4 in Fig. 1.

Fig. 5 is a vertical section taken along the line 5—5 in Fig. 1.

Fig. 6 is a section taken along the line 6—6 in Fig. 3.

Similar numbers of reference refer to similar parts throughout the several views.

Referring in detail to the drawings, there is shown a portion of a retort 10 whose coal tube 11 is joined by means of a flange 12 to a trough 13, which is connected by a flange 14 to a transmission case 15 on which is mounted a driving motor 16. The motor 16 drives the coal feeding worm 13A and also drives the fan within the casing 17.

Over the trough 13 is placed a cover plate 18 having a circular opening 19 formed therein into which projects the lower end 20 of an inclined tubular neck 21 provided at its upper end with a tubular head 22, the axis of which is normal to the axis of the neck 21. Attached to one side of the head 22 is a gear box 23 in which journals the shaft 24 of the gear 25 and the shaft 26 whose pinion 27 meshes with the gear 25.

Integral with the pinion 27 is a pinion 28 which meshes with a gear 29 on the horizontal shaft 30 on the outer end of which is attached the sprocket 31. The shaft 30 journals in the horizontal portion 32 of the gear box 23. The portion 32 is rotatable with relation to the box 23 at the flanged joint 33 along the axis of the shaft 26. The member 32 is supported from the cover plate 18 by means of an upright rod 34. Motion is supplied to the sprocket 31 through the chain 35 from the

sprocket wheel 36 on the counter shaft 37, on which is secured a gear 38 which is driven from the transmission 15.

The neck 22 is provided with a flange 39 which is held in place in relation to the cover plate 18 by means of the bolts 40. It will be observed that the axis 41 of the shaft 26 coincides with the axis of the opening 19.

The shaft 24 is joined by a universal joint 42 to an inclined coal conveying worm 43 which is coaxial with the head 22 and extends into the coal tube 44 which is joined to the head 22 by means of a bell end 45 to which it is attached by means of a screw 46. The coal tube 44 is joined by means of a flange 47 to a split angular connection 48, the edges of which are joined by means of the bolts 49. The interior 50 of the members 48 is somewhat enlarged midway between the ends thereof to provide the necessary clearance and to permit the worm 43 to assume an angular relationship to the worm 51 to which it is attached by means of the universal joint 52.

The worm 51 extends through the horizontal coal tube 53, which is attached to the members 48, and also projects through the clean out box 54 to which it is attached by means of the flanges 55. The clean out box 54 is provided with a removable V-shaped section 56, which is held in position by means of the bolts 57 and 58, the latter of which secure the clean out box 54 to the coal bin wall 59.

The portion 60 of the underside of the clean out box 54 extends through the wall 59 into the coal bin 61. The edge 62 of the portion 60 is formed spirally for reasons which will be explained later. The portion 63 of the worm 51 is preferably of a reduced diameter and is supported at its farther most end 64 by means of a tubular bearing 65, which is mounted on the coal bin wall 66. The portion of the worm 51 which 40 is almost as large as the interior of the tube 53 extends a short distance into the bin 61.

The purpose of reducing the diameter of the worm portion 63 is to avoid placing an objectionable load on the driving mechanism by conveying 45 more coal to the inlet of the clean out box 54 than can be carried into same by the worm 51. The purpose of inclining the edge 62 is to encourage the movement of the stones and tramp metal toward the upper edge 67 where they will 50 either enter the coal tube or jam at a point which is easily accessible when the section 56 is removed and without the necessity of taking out a lot of coal from the bin 61.

It may be seen from the foregoing that with 55

the arrangement herein described the neck 21 may be turned at any desired angle with relation to the trough 13 causing the device to lend itself to a wide range of installation requirements.

5 I claim:

1. A bin conveyer having in combination a trough, an inclined neck mounted over said trough and communicating therewith, a coal feeding worm within said trough, a tube communicating with the upper end of said neck, a worm within said tube, a driving connection on the upper side of said neck for rotating said last mentioned worm and a hinged joint for said driving connection coaxial with the lower end of said neck whereby said tube can be selectively fixed with relation to said trough.

10 2. A bin conveyer having in combination a horizontal trough, a coal feeding worm disposed within said trough having means for rotating same for the purpose of conveying fuel from said trough to a stoker retort, a sloping fuel conveying worm having its upper discharge end disposed above said trough, an inclined neck communicating between the upper end of said worm and said trough, gearing on the upper side of said neck for driving said fuel conveying worm,

15 said gearing having a pivotal axis passing through the junction of said neck and trough.

3. A bin conveyer for transporting coal from a bin to a retort of an underfeed stoker having in combination a horizontal coal tube communicating with the bin and having a worm therein extending into said bin, a sloping coal tube disposed above said horizontal coal tube, an inclined neck communicating between the upper end of said sloping coal tube and the horizontal coal 10 tube, a worm within said sloping coal tube and a drive gear on the upper side of said neck having a vertical pivotal axis passing downwardly through the junction of said neck and the horizontal coal tube, said neck and horizontal coal 15 tube being capable of a limited relative rotation.

4. A bin conveyer having a coal feeding worm enclosed within a coal tube and having a clean out box forming a portion of the coal tube communicating with a coal bin and having the lowermost portion of the communicating end projecting into said bin, said projecting end being formed spirally with its longest end terminating in a horizontal edge near the middle of the worm 20 25 height.

HASKELL C. CARTER.
